UNITED STATES PATENT OFFICE.

EDWARD P. DENNIS, OF LOWELL, MASSACHUSETTS, ASSIGNOR OF ONE-HALF TO J. S. LUDLAM, OF SAME PLACE.

MECHANISM FOR STRIPPING THE FLATS OF CARDING-ENGINES.

SPECIFICATION forming part of Letters Patent No. 291,471, dated January 1, 1884.

Application filed January 15, 1883. (No model.)

To all whom it may concern:

Be it known that I, EDWARD P. DENNIS, of Lowell, county of Middlesex, State of Massachusetts, have invented an Improvement in Mechanism for Stripping the Flats of Carding-Engines, of which the following description, in connection with the accompanying drawings, is a specification, like letters on the drawings representing like parts.

10 This invention relates to means for intermittently imparting fast and slow motion to the flat-stripping mechanism whereby the cam which actuates the arms carrying the stripper-card is automatically moved at a faster rate 15 of speed while the said stripper-card is operating to strip a raised flat.

My invention is an improvement on what is commonly known as the "Wellman Stripper" for carding-machines. In such machines the 20 axis of the main cylinder is driven by a belt running from one line of shafting, and the railway-head, doffer, and feed-rollers are driven from a different line of shafting. This 25 intermitting fast and slow motion of the said cam-gear has been produced in different ways. In one instance, as in United States Patent No. 244,546, the belt which drives the stripping mechanism and the said cam forming a part of it, has been shifted from the slow-speed pulley, 30 loose with relation to the shaft of the main cylinder, upon a fast-speed pulley secured to the outer end of the shaft of the main cylinder, and vice versa; but such plan is objectionable because both the said pulleys always move 35 and continue to operate the stripping mechanism as long as the main cylinder is rotated, notwithstanding the feed-rollers and doffer may have been stopped. Should the feed-rollers be stopped for any cause, the stripping 40 mechanism should also stop as soon as the top-flat then being stripped has been seated on the arch. In another plan, to increase the speed of the said cam, the short belt which drives the stripping mechanism has been 45 shifted outward at proper times from a loose slow-moving pulley driven from the shafting which actuates the feed-rollers and doffer upon the fast-speed pulley secured to the outer end of the shaft of the main cylinder; but in such 50 plan, if for any reason the feed-rollers and

doffer are stopped while the fast-speed pulley is operative, the short belt of the stripping mechanism, when shifted back from the moving fast-speed pulley, will, it will be seen, be shifted upon a pulley temporarily held fast by reason of the stoppage of the feed-rollers and doffer, and the belt and parts will be excessively strained. In the plan first referred to the fast and slow speed pulleys are so placed side by side that the loose pulley is always 60 loose and the belt is shifted from one to the other without strain.

To overcome the difficulties experienced in the two plans referred to, I have secured the high-speed pulley on the main shaft of the 65 carding-cylinder nearest the end of the said cylinder, and have placed the slow-speed loose pulley outside of it, nearer the outer end of the shaft of the main cylinder, thus giving it the 70 position heretofore occupied by the fast high-speed pulley in the plans referred to. The loose slow-speed pulley is chambered at its outer side and provided with a toothed ratchet, to be engaged by the pawls of a disk placed 75 loosely on the hub of the loose pulley, and the said disk, provided with an elongated hub, is driven by a belt extended over it and over a pulley on the shaft of one of the feed-rollers, and as the disk is driven its teeth engage the toothed ratchet fast on the loose slow-speed 80 pulley and drive it a slower speed than that of the high-speed pulley alongside of it and secured to the main shaft of the cylinder. The said fast and loose pulleys receive the 85 usual short belt which drives the stripping mechanism, as in the patent referred to, and the said belt, when it is to be shifted from the high-speed fast pulley, is moved laterally upon a loose pulley, which latter travels at the speed of the belt being shifted so long as the belt remains in contact with the high-speed pulley, the loose pulley traveling and moving with the said belt, but at a higher speed than that normally imparted to it by the pawl-carrying disk, the ratchet-teeth of the said loose pulley running forward at such time at a faster speed 90 under the pawls of the said disk and in the direction of the movement of the latter. Should the feed-rollers be stopped; the loose pulley 95 will not be temporarily held fast, as in the 100

plan referred to, but will remain loose to be run forward independently of the loose driving-disk, the rotation of which, with its pawls, is at such time arrested, and consequently I 5 avoid all jar or strain when shifting the belt.

Figure 1 represents in side elevation, partially broken out, a sufficient portion of a carding-machine to enable my invention to be understood. Fig. 2 shows the high and slow 10 speed devices in section and part of the main cylinder-shaft in elevation; Fig. 3, a view of one side of the slow-speed loose pulley, and Fig. 4 an inner side view of the pawl carrying loose disk.

15 The swinging and turning frame A of the stripping mechanism, having its fulcrum on the main shaft A² of the usual main cylinder, A³, is made to travel backward and forward by rack and gearing in the usual way.

20 The stripper B is carried by arms B²—one at each end of the main cylinder—and each arm is moved by a cam like that marked B³. These cams B³ are moved in customary manner by the usual gear, a b c, the gear a being 25 on a shaft provided with the belt-pulley d, over which is extended the usual belt, e, controlled as to its position by a belt-shipper, e², actuated by a cam, J, substantially as in the patent referred to, where the like cam is designated by the same letter. The shaft of the 30 main cylinder has on it at one end a pulley, (shown in dotted lines, Fig. 1,) over which is passed the belt f, which rotates the main cylinder and the high-speed pulley h, fast thereon.

35 (See Fig. 2.) The shaft g, driven from or in unison with the usual railway apparatus, has a pulley, g', which, by belt g², drives pulley g³ on shaft 2, and by gears g⁴ g⁵ drives the shaft g⁶, which in 40 practice will carry the usual doffer. The shaft 2 has a bevel-gear, m, which engages bevel-gear m' on the shaft m², having at its other end a bevel-gear, m³, which engages a bevel-gear, m⁴, on a short shaft, 3, having a 45 connected pinion, n, which engages a toothed gear, n', fast on the shaft n², of the usual under feed-roller of the pair of feed-rollers, which take the cotton from the usual lap or roll L and feed it to the main cylinder. The shaft 50 55 n² has on it a belt-pulley, n³, which drives the belt n⁴, extended over the hub p of the disk r, placed loosely on the hub s² of the slow-speed pulley s, loose on the main shaft A. (See Fig. 2.) The disk r has, as herein shown, a series 60 of pawls, r', some of which normally engage the teeth of the ratchet disk or plate t, attached by screws 4 to the loose pulley s within its chambered outer side. The disk r, when driven by the belt n⁴, as it will be so long as 65 the feed-rollers and doffer continue in motion, will, by its pawls r', drive the ratchet-disk and its attached loose pulley at a speed slower than that of the high-speed pulley h, fast on the main shaft A².

65 The pulley s is always free to turn in the direction of the arrow 6, (see Fig. 1,) notwithstanding the disk r, belt n⁴, and shafts n² and n³ have been stopped, and when the pulley s is driven by the belt n⁴ its speed is less than that of the pulley h, so that the belt e, whenever shifted from the high-speed pulley h upon the loose pulley, acts to carry the said loose pulley with it at the speed of the said belt, and that irrespective of the fact that the disk r is moving or stationary, as under both conditions the loose pulley will be taken up and moved by the belt e, and at its increased speed its ratchet-teeth will run ahead of and slip under the pawls r'. The belt n⁴ and disk r having been stopped, and a top-flat having been 80 stripped and returned to its seat on the usual arch, the cams B³ and J will have shifted the belt e wholly upon the loose pulley s, when further movement of the stripping mechanism will cease, notwithstanding the main shaft of 85 the carding-cylinder may be continued in motion.

70 By employing a loose pulley and disk and pawl and ratchet, as described, it is possible to turn the belt by hand and operate the stripping mechanism while the feed-rollers and doffer are at rest.

I claim—

1. The combination, substantially as hereinbefore set forth, with the main shaft A², the cylinder A³, stripping mechanism and frame A, which carries the same, of the high-speed pulley h fast on the shaft A², the slow-speed pulley s outside of it and loose on the said shaft, the ratchet-plate rotating with said slow pulley, the loose disk and its pawls, and means to rotate the said disk independently of the main shaft, as and for the purpose set forth.

2. The shaft n² of the feed-roller, belt-pulley thereon, belt n⁴, actuated by it, and the 105 pawl-carrying disk driven by the said belt, the shaft A², and the slow-speed loose pulley and its ratchet, combined with the high-speed fast pulley, the belt e², belt-shipper, and means to actuate it, substantially as and for the purpose described.

3. The main shaft A² and high-speed fast pulley thereon, combined with a slow-speed loose pulley placed at the side of it, the ratchet-wheel attached to the said pulley, and the 115 loose disk provided with a series of pawls, and means to rotate the said disk at a speed slower than that of the high-speed pulley, and a belt-shipper and belt whereby when the said belt is shifted from the high to the slow speed 120 pulley the latter pulley is moved at a speed corresponding with that of the belt, and its ratchet-teeth are moved forward under the teeth of the said pawls irrespective of the movement of the said disk, substantially as 125 and for the purpose set forth.

4. The shaft A², means to move it, the pulley h fast thereon, the pulley s loose thereon, the disk r, loose with relation to the said shaft and the said loose pulley, means between 130 the said loose pulley and disk to permit the said disk to turn the said pulley with it in one

direction only, and a belt to drive the said disk and means to drive the said belt, combined with a belt driving the said fast-pulley, stripping mechanism driven by the said belt, and a shipper to move the said belt from the fast to the loose pulley, the combination being and operating substantially as described, whereby the belt shifted from the fast to the loose pulley moves the latter at a speed faster

than the speed of the said loose pulley derived to from the said disk.

In testimony whereof I have signed my name to this specification in the presence of two subscribing witnesses.
